CLAIM

We claim the ornamental design for a combined outer shell and internal plug for a planting system, as shown and described.

DESCRIPTION

FIG. 1 depicts a perspective view of a combined outer shell and internal plug for a planting system with the top cover removed depicting an internal plug.

FIG. 2 is a front elevational view of the combined outer shell and internal plug for a planting system.

FIG. 3 is a rear elevational view of the combined outer shell and internal plug for a planting system.

FIG. 4 is a side elevational view of the combined outer shell and internal plug for a planting system.

FIG. 5 is an opposite side elevational view the combined outer shell and internal plug for a planting system.

FIG. 6 is a top plan view the combined outer shell and internal plug for a planting system depicting the internal plug.

FIG. 7 is a bottom plan view the combined outer shell and internal plug for a planting system.

FIG. 8 depicts a perspective view of the internal plug removed from the combined outer shell and internal plug for a planting system of FIGS. 1-7.

FIG. 9 is a front elevational view thereof.

FIG. 10 is a rear elevational view thereof.

FIG. 11 is a side elevational view thereof.

FIG. 12 is an opposite side elevational view thereof.

FIG. 13 is a top plan view thereof.

FIG. 14 is a bottom plan view thereof.

FIG. 15 depicts a perspective view of the combined outer shell and internal plug for a planting system with the top cover removed depicting a second embodiment of the internal plug.

FIG. 16 depicts a top view of the combined outer shell and internal plug for a planting system depicting the second embodiment of the internal plug.

FIG. 17 depicts a perspective view of the second embodiment of the internal plug removed from the combined outer shell and internal plug for a planting system of FIGS. 8-16.

FIG. 18 is a front elevational view thereof.

FIG. 19 is a rear elevational view thereof.

FIG. 20 is a side elevational view thereof.

FIG. 21 is an opposite side elevational view thereof.

FIG. 22 is a top plan view thereof.

FIG. 23 is a bottom plan view thereof.

FIG. 24 depicts an exploded view of the components of the combined outer shell and internal plug for a planting system with the first embodiment of the internal plug; and,

FIG. 25 depicts an exploded view of the components of the combined outer shell and internal plug for a planting system with the second embodiment of the internal plug.

The broken lines in the drawings illustrate environmental structure on the article and form no part of the claimed design.
